UNITED STATES PATENT OFFICE

JOHN C. BROOKS, OF PATERSON, NEW JERSEY.

LOOM.

1,405,096.

Specification of Letters Patent. Patented Jan. 31, 1922.

Application filed October 2, 1918. Serial No. 256,589.

To all whom it may concern:

Be it known that I, JOHN C. BROOKS, a citizen of the United States, residing at Paterson, county of Passaic, State of New Jersey, have invented an Improvement in Looms, of which the following description, in connection with the accompanying drawing, is a specification, like characters on the drawing representing like parts.

10 This invention relates to looms and particularly to looms of that type which are constructed to carry each pick of weft thread through the shed by means of an air blast instead of by means of the ordinary shuttle, 15 and the object of the invention is to provide a novel means for measuring each pick of thread and for blowing it across the shed; to provide a loom of this type which is constructed so that wefts of different colors can 20 be used; and otherwise to improve looms of this nature, all as will be more fully set forth.

In order to give an understanding of my invention, I have illustrated in the drawings an embodiment thereof which I will now describe, after which the novel features will be pointed out in the appended claims.

Figure 1 is a front view of a loom embodying my invention;

Fig. 2 is a side view of parts of the loom;

Fig. 3 is an enlarged front view of the end of the lay carrying the weft measuring 35 device;

Fig. 4 is a section on the line 4—4, Fig. 3;

Fig. 5 is a fragmentary side view showing the means for operating the weft measuring device;

40 Fig. 6 is a top plan view of Fig. 5;

Fig. 7 is a fragmentary view showing in side elevation the weft cutting device;

Fig. 8 is a top plan view of Fig. 7;

Fig. 9 is a front view of Fig. 7.

45 1 indicates a loom frame, 2 the lay which is carried by the usual lay swords 3 that rise from and are supported on the rock shaft 4, and 5 indicates the harness frames. These parts may have any suitable or usual construction.

50 The improved loom herein shown comprises a weft measuring device carried by the lay and by which predetermined lengths of weft thread may be measured off from a bobbin or other source of supply, a weft-delivery nozzle or nozzles to which the weft

threads are delivered from the weft-measuring device, and means for creating an air blast through said nozzle or nozzles to blow said lengths across the open sheds. In the 60 illustrated embodiment of my invention a construction is provided capable of handling a plurality of separate wefts which may be of different colors, said construction being arranged so that any one of the individual 65 wefts may be brought into use according to the pattern which it is desired to produce in the woven fabric.

One end of the lay 2 is provided with two vertically-extending guides 6 in which is 70 mounted for vertical movement a frame 7 carrying the weft measuring devices and weft delivery nozzles through which the weft ends are delivered to the shed. The weft delivery nozzles are shown at 8 there being 75 one nozzle for each separate source of weft thread supply. In the construction illustrated I have shown two weft nozzles thus permitting the use of two different weft threads. These nozzle tubes 8 extend across 80 the frame 7 and the weft threads 9 and 10 are led into the outer ends of said tubes, are carried through the tubes and are delivered from the inner ends thereof. Each nozzle tube 8 has a pipe connected thereto between 85 its ends and preferably near the delivery end thereof and through which air may be forced, the blast of air thus created serving to blow the weft from the delivery end of the nozzle tube across the shed. The two 90 air pipes are indicated at 11 and 12 respectively and they communicate with the nozzle tubes adjacent the delivery ends thereof.

Suitable means are provided for moving 95 the frame 7 carrying the weft nozzles 8 in a vertical direction so as to bring either nozzle into position to throw the weft therein across the open shed when the lay moves backwardly depending upon which weft it is 100 desired to use at any pick, and means are also provided for controlling the delivery of air through the flexible pipes 11 and 12 so that the air blast will always be delivered through the pipe leading to the particular 105 nozzle which is in line with the shed. The means for shifting the frame 7 vertically comprises an arm 13 depending from said frame and guided in its lower end in a bracket 14 secured to and carried by the 110 rock shaft 4. This arm 13 has a link 330 pivoted thereto at 331, and said link is pivoted

at 16 to one end of a lever 15, the other end of said lever being pivoted to the loom frame 1 at 17 (see Fig. 2). Said lever has a rod 19 connected thereto at 18 which rod is pivotally connected at its upper end to a pattern controlled lever 20 that is pivoted to the loom frame at 21. 22 indicates a shaft journaled on the loom frame which is provided with suitable pattern mechanism 23 in the form of a pattern cam or a pattern chain which acts on the lever 20 and raises and lowers it. Such pattern controlled rising and falling movement of the lever 20 will be communicated through the member 19 and lever 15 to the stem 13 thereby producing a corresponding shifting movement of the frame 7. The shaft 22 may be operated in any suitable way. I have herein shown it as actuated by a pawl and ratchet mechanism controlled from the usual crank shaft 24 by which the lay is operated. Pivotally mounted on the shaft 22 is a pawl carrying arm 25 which sustains a pawl 26 that co-operates with a ratchet 27 fast on the shaft 22. This pawl-carrying arm 25 is connected by a link 28 to a cam lever 29 pivoted to the loom frame at 30 and acted upon by a cam 31 on the crank shaft 24. Each rotation of the crank shaft 24 will thus move the shaft 22 forward one step and the pattern mechanism 23 on said shaft will determine which of the weft nozzles is brought into operative position. The means for producing the necessary air blast for blowing the weft across the shed comprises a pump cylinder 32 secured to the lay sword 3 and having therein a piston, the piston rod 33 of which is connected to a lever 34 pivoted to the loom frame at 340. The upper end of the lever has a pin 35 therein which is received between two shoulders 36 formed on an actuating bar 37 that is pivoted to a bracket 38 secured to the lay. Hence at each backward movement of the lay the lever 34 will be turned to give the plunger or piston of the pump a forward movement thereby to deliver an air blast therefrom and at each forward movement of the lay the pump piston will be withdrawn. The pump has a flexible pipe 39 connected thereto which leads to a valve mechanism indicated generally at 40 that determines whether the air blast shall be delivered to the pipe 11 or the pipe 12. This valve mechanism is operated automatically by the movement of the frame 7 so that the air blast will always be delivered to the nozzle 8 which is situated in operative position. While any suitable valve may be used I have herein shown a valve comprising a valve casing 41 to which the pipes 39, 11 and 12 are connected and which is supported on a bracket 43 rigidly secured to the depending arm 13 of the frame 7, and a valve plug 44 in the valve casing provided with a port 42 that is adapted to be brought

into communication with either of the pipes 11 or 12. The valve plug 44 has an arm 45 rigid therewith which is pivotally connected to a bracket 46 depending from the lay. As the frame 7 rises and falls the valve will move with it and because the arm of the valve plug is connected to the bracket 46 the vertical movement of the valve will turn the valve plug to bring the port 42 into communication with either pipe 11 or 12 depending upon the position of the frame.

Associated with each nozzle tube 8 is a weft measuring device constructed to draw off and measure a length of weft sufficient to reach across the shed. Each weft measuring device comprises a measuring wheel 47 journaled in the frame 7 and a presser wheel 48 which rests on the weft measuring wheel and means to rotate positively the weft measuring wheel. Each nozzle 8 is provided with an opening in which the wheels 47 and 48 operate so that the weft thread which passes through each nozzle will pass between the two wheels. The presser wheel 48 is carried by a lever 49 that is pivoted to the frame 7 at 50. The means herein illustrated for positively rotating the weft measuring wheel 47 comprises a pinion 51 rigid with said weft measuring wheel and which meshes with a gear 52 that has a pinion 53 integral therewith which pinion in turn meshes with a segmental gear 54. The segmental gear 54 is carried by an elbow lever 55 pivoted to the frame 7 at 56. The arm 57 of said elbow lever is offset and the offset end thereof is adapted to enter between two lugs or projections 178 extending rearwardly from the upper end of an elbow lever 58 pivoted at 59 to the lay. The elbow lever 58 is connected by a link 60 to an arm 61 fast on a rock shaft 62 journaled on the lay sword 3. Said rock shaft has another arm 63 fast thereon which is connected by a link 64 to one end of a lever 65 pivoted to the lay sword 3. The other end of said lever 65 is connected by a link 66 to a cam actuated lever 67 and pivoted to the loom frame 68. The lever 67 has a roll or pin 69 which operates in a cam groove 70 formed in a cam 71 fast to the cam shaft 72. The downward movement of the lever 67 will operate through the connections above described to rock the elbow lever 58 about its pivot 59 and thereby turn the segmental gear 54, the turning movement of said gear operating to positively rotate the measuring wheel 47. The linkage connection between the cam lever 67 and the lever 65 permits the vibrating movement of the lay without affecting the operative connection between said lever 67 and the lever 65. The cam groove 70 is arranged so that the forward rotative feeding movement of the measuring wheel 47 will occur as the lay approaches the backward limit

of its movement and while the pump 32 is being operated to deliver the air blast through one of the nozzles 8. At each pick of the loom therefore a length of weft will 5 be measured off and at the same time the said length will be blown across the open shed.

There is a weft measuring device for each 10 of the weft nozzles 8 and the construction is such that each weft measuring device will be brought into operative relation to the elbow lever 58 when the corresponding weft nozzle is in operative position.

It will be remembered that the offset portion 57 of the elbow-lever 55 is received between two lugs or projections 178. These lugs or projections form between them an open-ended vertical space or groove through which the offset portion 57 of the elbow- 20 lever 55 may move as the frame 7 is shifted vertically. Fig. 1 shows the frame 7 in its elevated position and the offset portion 57 of the lower lever 55 occupies the space between the lugs 178 in the lever 58. When 25 the frame 7 moves downwardly to bring the upper nozzle into position to deliver a weft across the shed, the offset portion 57 of the lower elbow-lever 55 will move downwardly out of the space between the lugs 178, and 30 the offset portion 57 of the upper lever 55 will be carried into such space. The downward movement of the frame 7, therefore, disturbs the operative connection between the lever 58 and the lower lever 55 and est- 35 tablishes an operative connection between said lever 58 and the upper lever 55.

The means for operating the weft measuring wheel is constructed to give it a rotation first in one direction to draw off and 40 measure a length of weft and then to rotate it in the reverse direction. In order that the weft may not be drawn back during the reverse rotative movement of the weft measuring wheel, I have provided for raising 45 the presser roll from the weft measuring wheel during such backward rotative movement.

Each lever 49 is provided at its forward end with a slot 73 in which operates a pin 50 74 carried by a lever 75 pivoted at 76 to the frame 7, the lower end 77 of said lever being offset and adapted to be received between two projections similar to the projections 178 on the lever 58 and which extend 55 from the upper end of the vertical arm of an elbow lever 78 pivoted to the lay at 79, said lever being similar to the lever 58. This lever 78 is connected by a link 80 to an arm 81 on a rock shaft 82 said rock shaft 60 having another arm 83 thereon which is connected by a link 84 to one end of a lever 85 that is pivoted to the lay sword 3, the other end of said lever being connected by a link 86 to the end of a cam lever 87 simi- 65 lar to the lever 67 and pivoted to the loom

frame at 88. This lever 87 has a roll 89 extending therefrom which operates in a cam groove 90 formed in the cam 900. The cam groove 90 is so shaped and timed as to turn the lever 75 in a direction to raise 70 the arm 49 thereby carrying the presser roll out of contact with the weft measuring wheel during the time that the said wheel is being rotated backwardly. Each lever 49 is provided with a gripping projection 91 75 adapted to enter a notch 92 in the nozzle 8 and grip or pinch the weft thread when the lever 49 is raised so that during the backward movement of each weft measuring roll the weft thread will be held by the pro- 80 jection 91.

The construction of the levers 75 with their offset ends 77 is such that as the frame 7 is raised or lowered to bring the different weft nozzles into operative position the cor- 85 responding levers will be brought into operative engagement with the elbow lever 78 in a manner similar to that in which the offset portions 57 of the levers 55 are brought into and out of operative engage- 90 ment with the lever 58.

After each pick of weft has been blown through the open shed as above described and during the following forward movement of the lay said pick will be severed adjacent 95 the delivery end of the nozzle 8. The thread severing means comprises a blade 93 secured to the breast beam 94 and having a second blade 95 pivoted thereto at 96, said second blade having a depending arm 97 that is 100 adapted to be engaged by a bunter 98 carried by the lay 1 (see Figs. 7, 8 and 9). Pivoted on the movable blade 95 is a weft-bending arm 99 having a depending arm 100 that is also adapted to be engaged by 105 the bunter 98. As the lay beats forward the bunter will engage the arms 100 and 97, thus swinging the weft-bending member 99 and the blade 95 downwardly onto the weft adjacent the end of the nozzle, the member 110 99 acting to bend the weft somewhat and the blade 95 operating to cut the weft adjacent the edge of the cloth. The end of the bunter 98 is shown as having two operative faces 101, 102 situated to act on the 115 arms 100 and 97, respectively, this construction being employed so that the weft-bend- ing arm will first be moved downwardly onto the weft, after which the cutting blade 95 will be moved. The weft-bending arm 120 puts a kink into the weft which is highly advantageous as the kink offers a resistance to the air blast, thus facilitating the carrying of the weft through the shed and ensur- ing that the weft will be drawn tight. 125

While I have shown herein a construc- 130 tion in which the silk thread or yarn which is made directly from the cocoons is deli- vered to a loom in which it is woven into a fabric, yet it will be obvious that so far

as the operation of the device for forming the silk thread or yarn is concerned, said device might deliver the yarn to other textile machines, such, for instance, as knitting machines, lace-making machines, embroidery machines, sewing machines, etc.

I claim:

1. In a loom, the combination with shed-forming mechanism, of a plurality of weft nozzles adapted to deliver weft to the shed, means to bring any one of the nozzles into position to deliver its weft to the shed, means for blowing the weft from the positioned nozzle across the shed, and weft-measuring rolls one for each nozzle to measure the weft as it is delivered to the shed.
2. A loom such as described in claim 1 having a common actuator for all of the rollers and means by which the actuator is placed in operative relation to any nozzle when the latter is brought into operative position.
3. In a loom, the combination with shed-forming mechanism, of a plurality of weft nozzles adapted to deliver weft to the shed, means to bring any one of the nozzles into position to deliver its weft to the shed, means for blowing the weft from the positioned nozzle across the shed, and means rendered operative by the shifting of the nozzles to control the weft-blowing means.

4. In a loom, the combination with shed-forming mechanism, of a plurality of weft nozzles each adapted to deliver a weft thread to the shed, means to bring anyone of said nozzles into operative position to deliver its weft to the shed and means to deliver an air blast through the positioned nozzle only, whereby the weft from said nozzle will be delivered to the shed while the weft carried by the other nozzles will be undisturbed.

5. In a loom, the combination with shed-forming mechanism, of a plurality of weft nozzles each adapted to deliver a weft thread to the shed, means for selectively actuating said nozzles to bring anyone into operative position to deliver its weft to the shed, means to develop an air blast, and means operating automatically to direct the air blast into the nozzle which is in operative position.

6. In a loom, the combination with shed-forming mechanism, of a plurality of weft nozzles, each adapted to deliver a weft thread to the shed, means to bring anyone of the weft nozzles into operative position to deliver its weft to the shed, means to generate an air blast and a valve device to direct the air blast to the positioned nozzle.

In testimony whereof, I have signed my name to this specification.

JOHN C. BROOKS.
